UNITED STATES PATENT OFFICE

2,514,698

CLOTHESPIN

José Antonio Herrero, Mexico City, Mexico

Application January 30, 1948, Serial No. 5,350
In Mexico February 18, 1947

2 Claims. (Cl. 24—137)

1

This invention relates to clothes pins.

The prime object of the invention is to provide a clothes pin having two clamping members pivoted together by a coiled spring and an interposed disk, the spring normally clamping the members together and the disk holding the two members from sidewise movement.

In the drawing:

Figure 1 is a perspective view of the clothes pin.

Figure 2 is a side elevation of the same.

Figure 3 is a top plan view.

Figure 4 is a top plan view of the spring and disk.

As shown in the accompanying drawing, the clothespin comprises two similar members 10 and 11 which are placed in inverted position with regard to each other, said members making up the body of the clothespin with the fastening ends 12 and spacing ends 13. Each of the spacing ends 13 of the members 10 and 11 making up the clothespin is considerably tapered, as may more easily be appreciated from the showing in Figure 2 of the drawing, to keep them apart from each other, so that on being pressed together, the opposite ends 12—which fasten the clothes or articles to which the pin is applied—may open or separate from each other. These same ends 13 are provided with respective longitudinal grooves or cuts 14 starting approximately from the centers of the members 10 and 11 and terminating at the outer free ends thereof.

These same members 10 and 11 have, on their inner face or surface, transverse grooves 15 and 16 that are common to this type of devices to support the pin on the clothesline, etc. When the clothespin members are assembled, the disk 17, previously mounted on the spring 18 is placed in the grooves 14, formed in the members 10 and 11 as stated above; to which purpose the disk is provided with a central hole, which is partially visible in Figs. 1 and 2.

The spring 18 has its ends extended so as to form the lever arms 19, the bent ends of which are inserted into transverse grooves 20 formed in the outer face of each of the members 10 and 11 making up the body of the clothespin, so as to cause said spring to keep its place and to exercise the right pressure on said members.

As will be understood, the disk 17 forces the members 10 and 11 into perfect alignment, thus avoiding excessive lateral play between the two

2

members, which might cause the latter to become separated.

Having thus described the invention, what I consider as new and desire to secure by Letters Patent is:

1. A clothespin comprising two members, each member formed with a longitudinal slot, each member having a transverse groove formed on its inner face, a coil spring seated in the transverse grooves forming a pivot for the two members, and a disc mounted on the coil spring and fitting in the slots formed in the members, one end of the coil spring being extended and bent to fit in a groove formed in the outer surface of one of the members, and the opposite end of the coil spring being extended and bent to fit in a groove formed in the outer surface of the other member.
2. A clothespin comprising two members, a spring including a coiled portion seated in grooves formed on the inner faces of the two members, one end of the spring extending from the coil and bent at right angles to overlie the outer surface of one member, the opposite end of the spring extending from the coil and bent at right angles and opposite the direction of the first-mentioned bent end and overlying the surface of the opposite member, and a disc mounted on the coiled portion of the spring and fitting in slots formed in the two members.
